UNITED STATES PATENT OFFICE

2,435,254

DYNAMIC STRAIN PICKUP

Walter Ramberg, Chevy Chase, Md.

Application September 25, 1945, Serial No. 618,597

3 Claims. (Cl. 201—52)

(Granted under the act of March 3, 1883, as
amended April 30, 1928; 370 O. G. 757)

1

My invention relates generally to apparatus for detecting vibrational displacements, and more particularly to the pick-up component therefor.

The principal advantage of this pick-up over presently available pick-ups is its exceptionally large voltage variations for small vibrational displacements. The output is ample to operate high frequency recording galvanometers directly without the complication of high frequency oscillators and amplifiers.

A useful application would be the recording of vibration on aircraft in flight. Another promising application is in resonance fatigue tests in which the output of a vibration pick-up mounted on the resonant specimen is used to hold the frequency of a driving motor at resonance; difficulties have been experienced with pick-ups in the past art because of their insufficient output.

For a more complete understanding of the invention and for other objects and advantages thereof, reference should now be had to the following descriptions in connection with the accompanying drawings, in which

Fig. 1 is a half-sectional view of my invention for detecting vibrational displacements, connected into a Wheatstone bridge circuit;

Fig. 2 is a view taken along line 2—2 of Fig. 1;

Fig. 3 is a view taken along line 3—3 of Fig. 1; and

Fig. 4 is a view taken along line 4—4 of Fig. 1.

Numeral 1 indicates generally a rectangular cross-sectioned housing, closed at each end. Centrally of one side, and projecting inwardly of said housing, is provided a normally projecting cylindrical stub element 2. The opposite side is centrally apertured 3 across which are secured two tandem spaced flexible plates 4 and 5 which have a sufficiently high natural frequency to respond to vibrations of a high order. Said plates are centrally apertured to receive assembly screw 6 and are secured to the housing by sliding their end portions into horizontal receiving slots 7 and 8 and peening said ends secure in said slots.

A cylindrical thrust element 9 is provided consisting of cylindrical sections 10, 11, 12 and 13 which are centrally apertured to receive assembly screw 6. End section 13 is threaded to threadedly engage said screw 6. An elongated abutment member 14 and a conducting leaf spring 15 are likewise centrally apertured to receive assembly screw 6. The above said elements are arranged, assembled and secured to the flexible plates by means of assembly screw 6 in the following order: assembly screw 6, section 10, leaf spring 15, abutment member 14, section 11, flexible plate

2

5, section 12, flexible plate 4, and threaded section 13. Section 13 threadedly engages screw 6 thereby allowing the screw to draw and secure said assembled elements tightly together and be carried by said flexible plates. Spring 15 and its abutment 14 are positioned parallel to each other so as to be in juxtaposed relationship through all deflection of said spring.

Stub element 2 is diametrically bored to receive 10 non-conducting rodular member 16 which is fixed and supported thereby intermediate said rod's ends. A fine resistance wire 17 is coiled around one end of said rodular member 16 in closely wound coils and is then connected into a Wheatstone bridge 18 as one arm thereof. Each individual turn of wire is insulated from its companion turn. The other end of said rod functions as an abutment for a leaf spring element 19 about to be described. Conducting leaf spring 19 is 15 centrally apertured and secured to the top of stub element 2, in a position parallel to the axis of coil 17, by means of screw 20 and washer 21. The stub element 2 projects beyond the received rodular element 16 a distance equal to the thickness 20 of coil 17 so that the leaf spring 19 secured in position will just overlay the resistance coil 17 tangentially. That part of leaf spring 19 that bears on said resistance coil is surfaced with a metal that has a small contact resistance at low 25 contact pressures, thereby making excellent contact with coil 17.

Said leaf springs 15 and 19 are welded together 30 at their ends 22, generally forming an elliptic spring, and provided with a particular configuration such that an approximately linear relationship obtains between the displacement of thrust element 9 and the current or voltage in the indicator 23 across the bridge 18. Said indicator 23 is responsive to electrical variations resulting 35 from the association of leaf spring 19 and resistance coil 17, whereby said configured leaf spring changes the extent of its bearing contact on said resistance coil by a change of the configuration of said spring 19.

40 In operation the thrust element 9 is held against any vibrating body to be investigated. The vibrational displacement causes the springs 15 and 19 to deflect. As leaf spring 19 deflects, it changes its configuration and increases the extent 45 of its bearing contact along coil 17. Thus progressively more and more turns are shorted out of the bridge circuit by spring 19, and the bridge is correspondingly unbalanced. Hence, any departure from a pre-determined and initial reading or reference point of the milliammeter 23

serves to detect a vibrational displacement. By suitable calibration, the milliammeter 23 is made to indicate strain directly. When the direction of the vibration is reversed, and the thrust element reverses its direction correspondingly, more and more coil windings are progressively "cut-in" to the bridge circuit, and the bridge is correspondingly "re-balanced."

While I have shown a particular embodiment of my invention, it will be understood, of course, that I do not wish to be limited thereto, since many modifications may be made, and I, therefore, contemplate by the appended claims to cover any such modifications as fall within the true spirit and scope of my invention.

The invention described herein may be manufactured and used by or for the Government of the United States of America for governmental purposes without the payment of any royalties thereon or therefor.

What is claimed is:

1. In a dynamic strain pick-up a housing having an opening in one side thereof, a flexible means of high natural frequency mounted on the housing across the opening and adapted to respond to vibrations, a thrust member mounted on the flexible means, a resistance coil having a supporting core, mounted in the housing transversely of the thrust member, and an elliptic spring having an electrical conducting leaf and a non-conducting leaf, the latter being secured to the thrust member and the former bearing on the resistance coil and adapted to deflectably extend its bearing contact along the coil to vary the current passing therethrough as a function of the displacement of the thrust member.

2. In a dynamic strain pick-up a housing having an opening in one side thereof; a thrust member flexibly mounted to operate through said

5

opening and adapted to respond to vibrations; resistance coil means mounted in said housing; and conducting elliptic spring means having the bottom of said spring means secured to said thrust member and the top of said spring means securely bearing on said resistance means and adapted to deflectably extend its bearing contact along said resistance in a linear relation to the displacement of said thrust member.

3. A dynamic strain pick-up including a housing having an opening in one side thereof, a flexible means spanning the opening, a thrust member operable through the opening and secured transversely to said means, a stub element depending from the side of the housing opposed to the opening, a resistance coil supported by said element, and a conducting elliptic spring interposed between the thrust member and stub element symmetrically positioned with respect thereto, and

progressively contacting the coil to shunt variable portions of the coil when acted upon by the thrust member.
